UNITED STATES PATENT OFFICE

102,064

DESIGN FOR A MEDAL OR SIMILAR ARTICLE

Dwight A. Parish, Vancouver, Wash.

Application September 17, 1935, Serial No. 58,597

Term of patent 3½ years

To all whom it may concern:

Be it known that I, Dwight A. Parish, a citizen of the United States, residing at Vancouver, county of Clark, and State of Washington, have invented a new, original, and ornamental Design for a Medal or Similar Article, of which the following is a specification, reference being had to the accompanying drawing, forming a part thereof.

In the drawing:

Fig. 1 shows the obverse, or front view, of the medal, the design of which is in relief, except the circular figure near the upper edge which is an insert or depression in which is mounted a piece of stone on a black background covered by a transparent disk held in place by a bezel;

Fig. 2 shows the reverse, or back view, of the medal; and

Fig. 3 is a sectional view taken on the line 3—3 of Fig. 1.

I claim:

The ornamental design for a medal or similar article, as shown and described.

DWIGHT A. PARISH.
